REENFORCING STRUCTURAL MEMBER

Arthur G. Leake, Bridgeport, Conn.

Application December 30, 1931, Serial No. 583,812

3 Claims. (Cl. 29—150)

This invention relates to reenforcing structural members, such as in building structures, bridges and the like, and has for an object to provide a method and means of reenforcing any of the structural members or any part thereof without tearing down the structure or disturbing the rivets, and which may be applied while the structure is in position and under load.

With the foregoing and other objects in view, the invention consists in a certain novel method and structure as will be more fully disclosed in connection with the accompanying drawing.

In the drawing:

Fig. 1 is a side elevation of a portion of a beam or girder showing the application of my invention;

Fig. 2 is a vertical section through the same substantially on line 2—2 of Fig. 1;

Fig. 3 is a top plan view of the structure in 20 Fig. 1; and

Fig. 4 is a detailed section on an enlarged scale substantially on line 4—4 of Fig. 3.

The invention consists broadly in reenforcing structural members, such as beams, trusses, columns, chords of trusses, webs of plate girders, built-up girders, and the like, where they have deteriorated, or if they are not deteriorated to increase their load carrying capacity, without disturbing the structure or the present rivet heads, and therefore it may be applied while the member being strengthened is left in position or is even under load. As illustrating the invention, I have shown it in the drawing as applied to a built-up girder, but as indicated above this 35 is merely by way of illustration, and the method and structure may be applied to various other structural members as indicated above.

The structural member shown comprises a web 10 with angle members 11 riveted to the opposite edges thereof by the rivets 12, and the structure strengthened by longitudinal plates 13 and 14 riveted to the outwardly extending flanges of the upper and lower angle members respectively by the rivets 15. If the structure is 45 deteriorated, or even though it is still in good condition and it is desired to strengthen it to carry a heavier load, with my improved method the structure can be strengthened without disturbing the heads of the rivets and without disturbing the structure. I accomplish this by 50 taking a new structural member of any desired shape or section and provided with openings of a spacing corresponding to the spacing of the rivet heads, and which openings are somewhat larger 55 than the rivet heads so as to provide a clearance

around the heads when the new member is placed against the old member. The holes or openings can be provided by punching, drilling or burning these holes, and after the paint, rust and scale has been cleaned from the surfaces of the old member, the new member can be applied against it and welded in position as will be more fully described. The paint, rust and scale can be removed by acetylene and oxygen torch, scraping the cleaning with a wire brush, and/or other cleaning tools.

In the specific illustration in the drawing a new cover plate 16 or 17 is provided with openings 18 by any suitable means, such as punching, drilling or burning, which openings are spaced to 70 correspond with the spacing of the rivets 15, and these openings are somewhat larger than the rivet heads to provide sufficient clearance for properly welding after the surfaces of the old member, as the top surface of the member 13 and the bottom surface of the member 14 are 75 properly cleaned and the new plate is placed against it. Then with the rivet heads in the openings 18, the edges of the openings are welded to the old plate or member 13 or 14 as the case 80 may be and to the head of the rivet as indicated at 19. This welding is preferably done by electric welding, although not necessarily so, and the weld metal 19 is thoroughly welded to the edges of the openings 18, the surface of the old structure is 85 indicated at 20, and to the head of the rivet, all as clearly shown in Fig. 4, making a uniform structure, and preferably filling up the space between the rivet head and the edges of the openings 18 flush with the top or outer surface of the new member. Then the edges of the new member 90 may be welded to the old member or the edges of the old member to the new member whichever happens to be the proper procedure and as required. At the top of the 95 girder shown in the drawing the new plate 16 is somewhat narrower than the old plate 13, and therefore the edges of the new plate are welded to the surface of the old plate as indicated at 21. At the lower part of the girder the new plate 17 is shown as of greater width than the old plate 14, and therefore here the edges of the old plate 14 are welded to the surface of the new plate 17 100 as indicated at 22.

Although as above described new plates 16 or 17 have been added to the old structure, it will be evident that the invention may be employed in the same manner for applying other strengthening members, such as angles, channels, beams, etc. It is to be noted that the weld 19 may be 110

applied simultaneously to the old member, the new member and the rivet head, and note is especially to be made of the increased circumferential value of the cross section of the rivet
 5 due to this welding. It will also be evident that this method of strengthening may be applied either to old structures which have been deteriorated to bring them up to their normal strength, or it is equally adapted for application to structures which have not deteriorated, but to which it is desired to add a new or additional section to enable it to carry an increased load.

Having thus set forth the nature of my invention, what I claim is:

15 1. The method of reenforcing structural members including members held together by rivets which comprises providing holes in a new cover plate, having said holes spaced to correspond with the spacing of the rivets and somewhat larger
 20 than the rivet heads, placing this plate against the structural member with the rivets in the openings, and welding the edges of the holes to the rivet heads and the old member and also welding the edges of the new plate to the old
 25 member.

2. The method of reenforcing structural structures including members held together by rivets which comprises providing a new structural member with openings of a size somewhat larger than the rivet heads and spaced to correspond therewith, placing the new member against one of the old members with the heads of the rivets in said openings, welding the new member in said openings to the old member and the rivet heads, and also welding edges of one of the old members to the new member.

3. A reinforced structure comprising structural members held together by rivets, a reinforcing member resting against one of said structural members having openings of somewhat larger diameter than the rivet heads and located with the rivet heads in the openings, welded connections about the edges of the openings securing the reinforcing member to the rivet heads and the old member, and welded connections between 95 edges of the reinforcing member and one of the structural members.
